UNITED STATES PATENT OFFICE.

EDWARD MAKIN, OF MANCHESTER, ENGLAND.

STEAM-GENERATOR.

1,104,811.

Specification of Letters Patent.

Patented July 28, 1914.

Application filed August 15, 1913. Serial No. 784,852.

To all whom it may concern:

Be it known that I, EDWARD MAKIN, a subject of the King of Great Britain, residing at 40 New Brown street, Manchester, 5 in the county of Lancaster, England, have invented new and useful Improvements in Steam-Generators, of which the following is a specification.

My invention relates to improvements in 10 steam generators of the type in which a primary generator is employed in the internally fired flue or other flues of the boiler. In one such form of primary generator, for which I obtained Letters Patent in Great 15 Britain No. 28689 of 1909, I employed a pipe coiled into a D shape or section and placed between the dead plate and the bridge, the coil being supplied at its inlet end with water under pressure by the direct action of 20 a pump or equivalent means while at the delivery end the coil was connected to the water space of the boiler. In a subsequent arrangement I employed a pressure header or reservoir containing feed water maintained at any required degree of pressure but 25 always at a sufficient pressure in excess of the boiler pressure, the feed water reservoir supplying any number of D coiled or similar primary generators fixed in the flues of a 30 battery of boilers and being placed in the most convenient position relatively to the said boilers. In this arrangement each D coil was supplied through a pipe connected to one end, preferably the front end, of the 35 coil and the circuit of circulation of steam and water was completed by a connection from the D coil to the water space of the boiler, the pressure header or reservoir being fitted with a pressure gage and the necessary 40 valves and taps being supplied to regulate the feed and the circulation. By this arrangement one pump or equivalent was able to supply the feed water for a battery of boilers instead of having a separate pump 45 for each boiler as necessary under the previous practice.

My present invention is designed to obviate the continuous working of the pump or other supply of feed water under pressure, 50 as for instance when fires are banked, or when little or no steam is required, as at meal times, and for this purpose I employ a relief pipe connected at one end to the feed pipe, which supplies feed water under pressure from the pressure header to the primary boiler, and at the other end I connect

this relief pipe to the boiler at a point above the internally fired flues. This relief pipe is connected to the pressure feed pipe at a point between an ordinary back pressure 60 valve, with which the latter is fitted and the primary generator, and is controlled by a stop cock or valve. This stop cock or valve is only opened when the pressure feed is shut off, as for instance when the fires are 65 banked or little or no steam is required at the times above indicated and when this is done the relief pipe forms a reverse circuit the water then flowing from the boiler through say the back to the front of the D 70 coil and thence through the relief pipe to the upper part of the boiler.

I illustrate an embodiment of my invention in the accompanying two sheets of drawings, in which—

Figure 1 is a front elevation, Fig. 2 a front sectional elevation and Fig. 3 a side elevation of a Lancashire or two flued boiler to which my improvements are applied. Fig. 4 is a detail view on a larger scale of 80 the feed pipe from the pressure header and the relief pipe from the boiler showing the arrangement of valves.

In these views, *a* designates the Lancashire or two flued boiler; *b* its two flues; *c* the pressure header or reservoir; *d* the feed pump which draws water from the boiler *a* through the pipe *e* controlled by a stop cock *f* and supplies water under pressure to the header or reservoir *c* through the pipe *g* 90 which is provided with a back pressure valve *h*; *i* the pipe supplying water under pressure from the header *c* to the D coiled or similar primary generator *l* placed in one of the flues *b* (or there might be two such 95 primary generators *l*, one in each flue); *j* a stop valve for controlling the supply pipe *i*; similar pipes *i'* *i''* may be connected from the pressure header to supply water to the like primary generators of other boilers, not 100 shown; *k* a back pressure valve on the supply pipe *i*; *l'* the circulating pipe from the back of the primary generator *l* to the boiler and *m* the stop valve for controlling the same; and *p* the pressure gage on the header or 105 reservoir *c*.

The relief pipe *n* which according to my present invention I connect to the boiler *a* above the level of the top of the flues *b* is controlled by a stop valve *o*, and at the other 110 end is connected to the pipe *i* (which supplies water from the pressure header *c* to the

primary generator *l*) at a point between the back pressure valve *k* and the primary generator.

By this combination and arrangement of 5 parts I obtain a positive circulation from the bottom of the boiler through the primary generator and back to the boiler again, whereby great efficiency and economy is attained.

- 10 When the fires are banked or when little or no steam is required, the pump *d* or equivalent is stopped, and the pressure feed is shut off by closing the stop cocks *f* and *j*, and the stop cock *o* is opened thus allowing 15 water to flow from the boiler *a* through the pipe *l'* to the back of the *D* coiled or like primary generator *l*, through the feed pipe *i*, and relief pipe *n* back to the boiler. In its passage through the *D* coiled or like primary generator *l* steam is generated and becomes highly heated and issuing from the relief pipe *n* meets the saturated steam in the boiler which acts upon the comparatively dry steam issuing from the relief pipe *n*, and by condensing it induces the flow of 20 steam through the relief pipe *n* and *D* coil *l*

and so automatically promotes and maintains a circulation in the reverse direction to that which the steam and water take when 30 the boiler is normally at work.

I declare that what I claim and desire to secure by Letters Patent is:—

In combination, a main generator having an internally fired flue, a primary generator 35 in said flue, a pressure header and pump, pipes connecting said header and said pump to said generators, a back pressure valve in the pipe between said header and said primary generator, a relief pipe having one end 40 communicating with the pipe between said primary generator and said valve and having its other end communicating with said main generator at a point above said flue, and a valve in said relief pipe. 45

In testimony whereof I have signed my name to this specification in the presence of two subscribing witnesses.

EDWARD MAKIN.
